United States Patent Office

Des. 216,718
Patented Mar. 3, 1970

216,718

CARD FILE CABINET

Peter J. Protzmann, Grand Rapids, Mich., assignor to Herman Miller, Inc., Zeeland, Mich., a corporation of Michigan

Filed Oct. 18, 1968, Ser. No. 14,059

Term of patent 14 years

Int. Cl. D6—01

U.S. Cl. D33—19

FIG. 1.

FIG. 2.

FIG. 5.

FIG. 4.

FIG. 1 is a perspective view of the card file cabinet;
FIG. 2 is a front elevation thereof;
FIG. 3 is a side elevational view taken from the right
in FIG. 1;
FIG. 4 is a plan view thereof; and
FIG. 5 is a rear elevation thereof.
The side opposite to that shown in FIG. 3 is a mirror image of that shown in FIG. 3.
I claim:
The ornamental design for a card file cabinet, substantially as shown and described.
